FUEL CUT-OFF

Russell G. Berry, De Soto, Mo., assignor to Carter Carburetor Corporation, St. Louis, Mo., a corporation of Delaware

Application January 2, 1934, Serial No. 704,977

8 Claims. (Cl. 123—119)

The present invention appertains to improvements in carburetors for internal combustion engines and more particularly to means for conserving fuel, and preventing excessive dilution of the crank case oil under certain conditions. This application is a continuation in part of applicant's co-pending application No. 463,100, filed June 23rd, 1930.

When an automobile is coasting down hill or coasting to a stop with the throttle closed and with the engine turning over at a speed corresponding to the speed of the automobile, a comparatively high vacuum exists in the intake manifold and fuel is supplied through the conventional 5 idling passage to the engine. Since no power is required from the engine under these conditions, all of the fuel supplied is wasted. These periods of coasting may be several miles in length as when coasting down a mountain with the engine in gear 10 to act as a brake. On the other hand the periods of coasting may be only a few feet in length as when coasting to a "stop" in city driving, or when momentarily slowing up the automobile. For long coasting periods of several miles in length 15 the operator may turn off the flow of fuel to the carburetor but this is not entirely satisfactory because the float chamber of the carburetor contains a substantial quantity of fuel and this fuel would be used up before the turning off of the flow 20 of fuel to the carburetor had any effect. Obviously this method of turning off the fuel cannot be used in coasting to a stop because the gasoline control valve in the line leading to the carburetor is usually under the hood and the operator would 25 have to get out of the car to operate it.

Another difficulty with previous carburetor constructions is what is known as percolation. Gasoline is composed of various hydrocarbons which boil anywhere from 106 degrees Fahrenheit to 450 degrees Fahrenheit. The temperature existing under the hood of an engine may be 200 degrees Fahrenheit or even more. The result is that boiling occurs in the carburetor and particularly in the upwardly directed passageways which 30 lead to the discharge outlet of the nozzle. The carburetor is, of course, connected to the engine and heat transferred thru the body of the carburetor is applied to the fuel in these small passageways first with the result that the lower boiling 35 constituents of the gasoline are vaporized and form small bubbles. These bubbles begin to work their way up to the outlet of the carburetor nozzle and begin to carry gasoline with them. In this manner a pumping action is set up which may 40 continue until the float chamber of the carburetor

is emptied. It will be understood, of course, that this condition is most serious after the motor has been thoroughly heated up by running and then brought to a stop. During the normal running of the automobile or internal combustion engine, 5 there is usually sufficient gasoline flowing thru the passages leading to the nozzle of the carburetor to cool the metal surrounding the passages and prevent the boiling or percolation.

A third difficulty with certain types of internal 10 combustion engines is that the operator may forget to turn on the switch or ignition prior to operating the self starter or cranking the engine. In such cases the engine may frequently become so flooded with gasoline that it will fail to start and 15 continued cranking only aggravates the difficulty.

The principal object of my invention is to overcome the three above described difficulties simultaneously by placing an electrically operated control valve in position to cut off the fuel supply at a 20 point between the float chamber of the carburetor and the nozzle and to operate this valve by a solenoid whenever the ignition switch of the engine is turned on and to close the magnetic valve whenever the ignition switch of the engine is 25 turned off.

A further object of my invention is to provide an additional switch which is more conveniently operated than even the ignition switch so that the operator can instantaneously cause the closing of 30 the gasoline control valve at any time without taking his hand from the steering wheel.

Other important objects and advantages of the invention will readily become apparent to the reader during the reading of the following specification and claims.

In the drawings:

Figure 1 represents a diagrammatic view disclosing the electrical connections by means of which the device is operated.

Figure 2 represents a diagrammatic sectional view disclosing a simple form of carburetor with the electro-magnetic valve mounted thereon.

Figure 3 represents a horizontal sectional view taken substantially on the line 3—3 of Figure 2.

Figure 4 is a vertical sectional detail view of the switch means.

Figure 5 is a diagrammatic vertical sectional view showing an improved form of my device.

Referring to the modification shown in Figures 1 to 4 of the drawings, it can be seen that numeral 5 in Figure 1, refers to the usual storage battery found on an automobile. The lead 6 extends from the battery and to the ammeter 7, from which a wire 8 extends to one side of the 50

ignition switch 9. One wire 10 extends from the other side of the ignition switch 9 to the usual spark coil 11. A second wire 12 extends from the ignition switch 9 to a switch unit generally referred to by numeral 13.

5 A wire 14 extends from the switch unit 13 into the electro-magnetic valve generally referred to by numeral 15, one side of which is grounded by the wire 16.

10 The switch generally referred to by numeral 13 includes a cover 17, the bottom of which is formed as a casing 18. The bottom of this casting 18 is normally closed by the plate 19. A plate 20 formed of insulating material is secured 15 to the under side of the floor plate 17 and carries a pair of stationary contacts 21-21, to one of which the wire 12 is secured and to the other the wire 14 is secured.

15 A tubular riser 22 is provided on the plate 17 and as clearly shown in Figure 4, a rod 23 is 20 slideable through this riser 22 and through an opening in the cover 17, to connect to the switch blade 24, located within the casing 18.

25 A cap 25 is secured to the upper end of the rod 23, and is mounted to telescope the upper end of the riser 22. A coiled spring 26 is interposed between the plate 17 and the cap 25 for normally maintaining the cap 25 raised with the blade 24 bridging the contacts 21-21.

30 The wires 12 and 14 are trained through an opening in the side of the casing 18.

35 As before stated, numeral 15 generally refers to the electro-magnetic valve which is located within the carburetor generally referred to by numeral 27.

40 The carburetor is provided with a carbureting chamber or mixing conduit 30 and the conventional float chamber or constant level chamber 40 in which the fuel is maintained at a substantially constant level indicated by the broken line 45 A-A by a conventional float 41 which controls the usual fuel inlet needle valve 42. It will be understood that fuel is supplied to the inlet passage 43 of the float chamber by any suitable means, many devices for this purpose being well known to the art.

50 A conventional main nozzle 29 and idling tube 28 are provided, and these are connected with the float chamber by means of the passage 31, the inlet of which is controlled by the electro-magnetic valve 34. A valve seat or bushing member 32 is preferably threaded into the inlet end of the conduit 31 for the purpose of conveniently forming a seat for the valve 34.

55 The electro-magnetic valve includes the coil 33, suitably secured to the carburetor shell. The valve element 34 is secured to the armature plate 35 and the guide stem 36 protrudes into the core of the magnet to guide the valve when in its normal elevated position.

60 It can now be seen that when the automobile is moving down-grade, the operator may depress the button 25 to break the connection between the contacts 21-21.

65 Obviously, when this connection is broken, the magnet 33 becomes de-energized thus permitting the valve 34 to drop and seat on the bushing 32. The fuel supply is now shut off and will not again flow until the operator releases the cap 25, whereupon the circuit will be restored and the magnet again energized to attract the valve 34.

70 Whenever the operator wishes to stop the engine he breaks the ignition circuit by operating the switch 9 which results in the de-energization 75 of the magnet 33 and the closing of the valve 34

so that there is no chance of boiling any more fuel out of the carburetor than is contained in the passages 31, 28 and 29. In fact the closing of the valve 34 usually prevents the loss of any fuel from either the nozzle 29 or the passageway 5 28.

10 In case the operator should start to crank the automobile without remembering to turn on the switch 9, there is no danger of flooding the engine with gasoline because the valve 34 remains closed until after the ignition is turned on by means of the switch 9.

15 Referring to the modification shown in Figure 5, the chief difference in principle between this construction and that previously described is that an automatic arrangement is provided for cutting off the fuel at all times when it is not actually needed to propel the motor. This takes the form of a suction operated switch generally indicated by the reference numeral 50 which is 20 mounted on the intake manifold.

25 The switch is so constructed as to be operated by the extremely high suction which is developed when the engine is running at faster than idling speed with the throttle closed. This suction condition in four cycle motors is well known to those skilled in the art but it may be briefly described as follows. Whenever the engine is running at full power or with the throttle wide open the highest suction that can be developed in the average intake manifold is not more than two or three pounds per square inch. If the throttle is gradually closed with the engine in operation the suction in the intake manifold, that is between the throttle and the engine, will gradually increase. 30 If the engine is running at high speed as it would be going down hill, under certain conditions, a suction of about ten or eleven pounds below atmospheric pressure is developed in the intake manifold. 40

Under these conditions there can be no advantage in supplying any fuel to the engine because no power is required from it. On the other hand, power is being applied to the engine from the rear wheels of the car to maintain the high speed and the engine is acting as a brake on the wheels. If the car ceases to go down hill, the speed will be reduced and the suction in the intake manifold will also be reduced. 45

The normal idling speed of the motor is in the neighborhood of two or three hundred revolutions per minute and at this speed the pressure in the intake manifold will be in the order of eight pounds below atmospheric. When the engine is running at this speed, fuel must be supplied to it or it would stop. The function of the switch 50 55 55 is to cause the supply of fuel to the engine to be cut off whenever the suction in the intake manifold is substantially in excess of the normal idling suction. 60

65 While certain specific figures in relation to the amount of suction developed have been used, these are merely illustrative. The normal idling suction of an engine depends to a great extent on the compression ratio of that engine. The present trend is toward higher compression ratios and if a sufficiently high compression ratio was used, the normal idling pressure might be ten or eleven pounds below atmospheric or even more, but my invention contemplates the 70 existence of at least some difference between the suction developed in the intake manifold at ordinary idling speeds and the suction developed therein at higher speeds when the throttle is closed. 75

In the construction shown in Figure 5, the switch 50 replaces the switch generally indicated in Figure 1, by the reference numeral 13. The reference numeral 52 indicates the main body 5 of a carburetor of well known downdraft construction. This carburetor is provided with a constant level chamber 40 in which the fuel is maintained substantially at the constant level A—A by the float mechanism generally indicated at 41, the details of which are well known and need no further description. The throttle valve is indicated by the reference numeral 53 and is mounted on shaft 54 which operates the lever 55. This lever operates the metering valve 56 by means of a link 57 which is connected to the rocker arm 58, the rocker arm being pivotally mounted as indicated at 59.

The metering rod 56 extends into and through the main jet 60, the central part of which is provided with a calibrated restriction 99, and the upper end of which is provided with the valve seat 61. A tubular valve 62 loosely surrounds the metering rod. This valve is made of soft iron or other suitable magnetic material 25 and forms a slidable core for the solenoid. The lower end of the tubular valve member 62 cooperates with the valve seat 61 to cut off the supply of fuel to the main nozzle 63 and idle passages 64 when the supply of current to the solenoid 65 is cut off. The idle passage terminates in the idle port 88. A spring 66 may be provided if desired to assist in holding the valve 62 firmly on its seat.

The switch casing 50 is provided with a flexible contact member 67 which is perforated at 68 to prevent the sticking of the member 67 in position to close the end of the passageway 69, or in other words in position to break the circuit and cause the closing of the valve 62. The passageway 69 is formed at its upper end of the valve seat to receive the member 67 of the valve and a restricted passageway 70 is formed in the passage 69 for the purpose of limiting the amount of air which may be admitted to the intake manifold when the member 67 is not in contact with the end of the passage 69. It will be understood that the casing 50 is vented as indicated at 71. The casing 50 is insulated from the engine by means of insulating gaskets 50 72 and 73.

The wiring connections for Figure 5 differ only slightly from the diagram shown in Figure 1. Like reference numerals 5, 6, 7, 8 and 9 refer to the same elements which are used in both Figures 1 and 5. Instead of placing the automatic switch member between the manual switch 9 and the electrically operated valve, the arrangement is reversed. A lead 74 conveys current to one connection of the solenoid 65 as indicated at 75. The outlet connection of the solenoid is indicated at 76 and this is connected by means of a conductor 77 to the insulated terminal 78 of the switch 50. This insulated terminal is in electrical communication with the 65 adjusting screw 79 which normally grounds the circuit thru the member 67 and the intake manifold 51 to the engine.

In operation the device is so adjusted as to prevent operation of the member 67 by normal idling suction or any suction below that. Whenever the normal idling suction is substantially exceeded, as when the vehicle is coasting in gear, the suction draws the member 67 against the 75 end of the passageway 69 breaking the contact

with the member 79 and venting the current through the solenoid 65, thereby permitting the valve member 62 to seat against the valve seat 61 and cut off the supply of fuel to both the main and idling nozzles. The device operates 5 on coasting down hills and even on coasting a few feet to a "stop" sign. While the amount of fuel supplied under idling conditions is comparatively small, the use of this device will normally result in a saving of substantially five 10 percent of the total amount of fuel used, at least during city driving. In hilly and mountainous country the saving will be substantially in excess of that.

A substantial advantage of this device relates 15 to the fact that in coasting down long hills and going down mountains, the engine is generally used as a brake. With the throttle in the normal idling position, the engine, without this device, is supplied with a very lean, slow burning 20 mixture which has a very substantial heating effect. This heating tends to keep the oil on the cylinder walls in a very thin and fluid condition, minimizing the braking effect of the engine. By 25 the use of this device the explosions in the cylinders are eliminated altogether during the coasting period, with the result that the oil is much more rapidly cooled and the braking effect of the engine is greatly improved.

The invention is not limited to the structure 30 as shown but may be modified in various respects as will occur to those skilled in the art, and the exclusive use of all such modifications as come within the scope of the appended claims is contemplated.

I claim:

1. In an internal combustion engine, an ignition circuit having a control switch therefor, a carburetor having a fuel supply chamber, a carbureting chamber, and a fuel passage connecting said chambers, valve means for controlling said fuel passage and means for closing said valve whenever said ignition circuit is broken, and means for closing said valve without cutting off said ignition circuit. 45

2. In a device of the class described, a carburetor, said carburetor having a constant level fuel chamber, a mixing conduit, and fuel passages leading from said constant level fuel chamber to said mixing conduit, means for cutting off the supply of fuel thru said passages when the carburetor is not in operation, and means for cutting off the supply of fuel thru said passages when the suction applied to said carburetor exceeds the normal idling suction. 55

3. In a carburetor, a constant level chamber, a main jet for conveying fuel from said chamber, a metering rod controlling said main jet, and a tubular valve surrounding said metering rod and movable therealong to seat against the upper 60 end of the said main jet to cut off the flow of fuel therethrough.

4. In a device of the class described, a carbureting chamber, a main fuel supply orifice therefor, a metering rod extending through and controlling said orifice, and a valve surrounding said metering rod and movable therealong to seat against the edge portion of said orifice and cut off the flow of fuel therethrough. 65

5. Structure as specified in claim 4 further including means responsive to the inoperative condition of the device for moving said valve to cut off said orifice. 70

6. Structure as specified in claim 4 in which 75

the device is constructed and arranged for application to a vehicle, said device further including means for moving said valve to cut off said orifice when the associated vehicle is coasting in gear.

7. In a device of the class described, a fuel mixture conduit, a passage for supplying fuel to said conduit, means for cutting off the supply of fuel through said passage when the device is inoperative, and means for cutting off said pas-

sage when the suction in said conduit exceeds normal idling suction.

8. In a device of the class described, a carburetor mixture conduit, a passage for supplying fuel to said conduit, means for cutting off said passage when the device is inoperative, and means for cutting off said passage when the associated engine is being driven by a force other than combustion in its firing chambers.

RUSSELL G. BERRY. 10
